UNITED STATES PATENT OFFICE

2,502,990

GOVERNOR CONTROL FOR DUAL FUEL ENGINES

Edward Rathbun, Toledo, Ohio, assignor to Rathbun-Jones Engineering Company, Toledo, Ohio, a corporation of Ohio

Application September 14, 1946, Serial No. 697,112

2 Claims. (Cl. 123—121)

1

This invention relates to high compression internal combustion engines but more particularly to such engines which are adapted to operate on gas or oil or a mixture of both gas and oil.

A dual fuel engine of the high compression oil ignition type may operate either on a maximum amount of gas and a minimum amount of oil, all oil and no gas, or intermediate proportion, but in that event, the two fuels must not exceed a certain value, depending upon the volume of air available for combustion. If the gas supply fails or is substantially restricted, the engine should automatically supply additional fuel oil to handle the load.

It is exceedingly difficult, if not impossible, at a practical matter efficiently to fulfill the above requirements with a single governor. Attempts have heretofore been made in this connection, but they involve exceedingly complicated and complex leverage and linkage systems which not only present many moving parts which are very difficult to be kept in proper adjustment, to compensate for bearing, wear, etc., but furthermore, in such an arrangement, it is patent that one portion of the governor motion must handle the gas and another portion the oil, so that either movement may be too sensitive or not sufficiently sensitive adequately under all conditions to accomplish the desired purpose.

An object of this invention is to overcome the difficulties inherent with a single governor.

In accordance with this invention, two governors are employed, one for the purpose of moving the gas supply valve between open and closed positions, and the other governor for the purpose of controlling the fuel oil supply, each of the governors operating through the normal range provided for it in the usual manner, and each being located on the engine to the best advantage for handling its respective fuel. Manifestly, the operation of two governors may be regarded somewhat like two engines operating in parallel, one being a gas engine and the other an oil engine. Consequently, if the speed of the gas engine governor is increased, the gas engine will take more of the load until finally the oil engine will be without load, such an arrangement in a gas oil engine corresponding to minimum oil and mostly gas operation. Let us assume that the gas and oil engines are running in parallel, the gas engine being loaded and the oil engine with no load. In such an event, if the gas is shut off the gas engine, the speed of both engines drops and the oil engine will then pick up its share of the load.

2

It will be manifest that the performance of two governors on one engine is the same so that if the governor controlling the gas is speeded up slightly, more gas and less oil will be used.

It is recognized that when a single governor is employed for controlling both the gas and oil supply to the engine, and the operating arrangement is such that the engine is operating at approximately rated load on gas, if the load is thrown off the engine, it will operate at no load on gas. However, if the load is suddenly thrown on again, the momentary drop in speed results not only in introducing full load gas, but also full load oil. This is an impossible operating condition, and would have dire results.

On the other hand, with the use of two governors as above mentioned, they may be interconnected in such a way that in such an event, the gas supply will be substantially reduced at the time that the full load oil is supplied. Thus by employing two governors, the difficulty mentioned in connection with the use of a single governor is obviated.

For purposes of illustration but not of limitation, an embodiment of the invention is shown in the accompanying drawings, in which the figure is a diagrammatic view showing the two governors, one for gas and one for oil, and the connection between them which becomes effective in the event the governors suddenly call for full load gas and full load oil at the same time.

Referring to the drawing, 10 designates a governor operatively connected to be driven by the engine, and for controlling the fuel oil supply to the engine. Detailed description and illustration of the governor is not considered necessary to a clear understanding of the invention. Suffice it to say that the governor 10 is of the variable speed type equipped with a control shaft 11 having a crank arm 12 to the end of which is pivoted a link 13 leading to a suitable valve 13a controlling the admission of fuel oil from the usual injection pump 13b to the engine, the crank arm 12 being adapted to rock vertically substantially to the extent indicated. When the valve 13a is closed, then full supply of oil is delivered to the engine, but opening of the valve enables a controlled amount of oil to bypass to a suitable reservoir, as will be readily understood by those skilled in this art.

It will be understood that in governors of this type, the control shaft 11 oscillates in accordance with the engine load conditions in one direction when more fuel is required, and in the

3

other direction when a lesser quantity of fuel is needed to keep the engine speed uniform. Variable speed governors of this type are well-known to those skilled in this art and are ordinarily available in the open market, one of which, entirely satisfactory for the purpose, being produced by Woodward Governor Company of Rockford, Illinois, and referred to as "Type U. G. 8 Governor."

Manifestly, the governor 10 can be located in any desired or convenient position on or juxtaposed to the engine.

In addition to the oil control governor 10 is a gas control governor 14 which is preferably the same type of governor as the oil control governor and the description above given with respect to the oil control governor applies equally well to this governor which is likewise equipped with a control shaft 15 having a crank arm 16 and a vertically disposed rod 17 connected to the outer end of the crank arm and connected at its upper end to the gas control valve 17a. As in the case of the oil control governor 10, the gas control governor 14 may be mounted in any suitable or desired location with respect to the engine.

For militating against full load gas as well as full load oil being simultaneously supplied to the engine in the event that the load is suddenly thrown on the engine after it has previously been operating at no load on gas, a yoke arm 18 is moved against a stop 19 on the rod 17 in such manner as to prevent abrupt opening of the gas control valve. The yoke arm 18 is mounted for rocking movements on a hydraulic receiver 20 which connects by a tube 21 to a hydraulic transmitter 22. The control shaft 11 of the oil governor extends into and is operatively connected to the operating mechanism of the transmitter. The hydraulic system which comprehends the transmitter 22, tube 21 and receiver 20 is not shown nor described in detail inasmuch as devices of this character are well-known to those skilled in the art and are obtainable on the market. For example, a satisfactory device of this character is produced by Sperry Products, Inc., of Hoboken, New Jersey, and referred to as Type HCO1-B.

It will be manifest from the above description that abrupt movement of the control shaft 11 of the fuel oil governor 10 operates through the hydraulic transmission device to actuate the yoke arm 18 against the stop 19 so that abrupt opening movement of the gas control valve is blocked. However, upon restoration of normal conditions, the yoke arm will be moved downwardly to permit predetermined operation of the gas control governor 14 to regulate the opening of the gas control valve.

It is to be understood that numerous changes in details of construction, arrangement and

operation may be effected without departing from the spirit of the invention especially as defined in the appended claims.

What I claim is:

1. In a dual fuel engine of the internal combustion type, the combination of a cylinder having a combustion chamber, gas fuel admitting means for said combustion chamber, an engine driven governor operatively connected to said gas fuel admitting means for admitting gas fuel in accordance with engine load demands, an oil fuel admitting means for admitting oil fuel to the combustion chamber, an engine driven governor operatively connected to said oil fuel admitting means for admitting oil fuel in accordance with the engine load demands, and mechanism operatively connected to and deriving movement from said second engine driven governor for closing said gas fuel admitting means in the event both governors called for full load fuel, said mechanism including a part actuated by said second governor, and a compensating element movable in response to said part to block opening movement of said gas fuel admitting means.
2. In a dual fuel engine of the internal combustion type, the combination of a cylinder having a combustion chamber, gas fuel admitting means for said combustion chamber, an engine driven governor operatively connected to said gas fuel admitting means for admitting gas fuel in accordance with engine load demands, an oil fuel admitting means for admitting oil fuel to the combustion chamber, an engine driven governor operatively connected to said oil fuel admitting means for admitting oil fuel in accordance with the engine load demands, and mechanism operatively connected to and deriving movement from said second engine driven governor for closing said gas fuel admitting means in the event both governors called for full load fuel, said mechanism including a shaft forming a part of and rotated by said second governor, and a compensating element movable in response to said shaft to block opening movement of said gas fuel admitting means.

EDWARD RATHBUN.
